(57) **CLAIM**

The ornamental design for a key chain fob, as shown and described.

DESCRIPTION

FIG. 1 is a pictorial view of a key chain fob according to the invention, with broken line depictions of a leg covering, a key chain, and functional details not forming a part of the invention.

FIG. 2 is a right side view of the key chain fob shown in FIG. 1

FIG. 3 is a left side view from the key chain fob shown FIGS. 1 and 2 with broken line depictions of a leg covering, a key chain, and functional details not forming a part of the invention.

FIG. 4 is a front view from the key chain fob shown in FIGS. 1-3 with broken line depictions of features shown in FIGS. 1-3 not forming a part of the invention.

FIG. 5 is a rear view from the key chain fob shown in FIGS. 1-3 with broken line depictions of features shown in FIGS. 1-4 not forming a part of the invention.

FIG. 6 is a bottom view from the key chain fob shown in FIGS. 1-3 with broken line depictions of features shown in FIGS. 1-5 not forming a part of the invention.

FIG. 7 is top view from the key chain fob shown in FIGS. 1-3 with broken line depictions of features shown in FIGS. 1-6 not forming a part of the invention.

FIG. 8 is a pictorial view of the key chain fob according to the invention with the shoe and the key chain and other features shown in broken lines, not forming a part of the invention.

FIG. 9 is a right side view of the key chain fob shown in FIG. 8, with broken line depictions of features not forming a part of the invention.

FIG. 10 is a left side view of the key chain fob shown in FIGS. 8 and 9.

FIG. 11 is a front view of the key chain fob shown in FIGS. 8-10.

FIG. 12 is a rear view of the key chain fob shown in FIGS. 8-11.

FIG. 13 is a bottom view of the key chain fob shown in FIGS. 8-12; and,

FIG. 14 is a top view of the key chain fob shown in FIGS. 8-13.
